United States Patent Office

Des. 177,236
Patented Mar. 27, 1956

177,236

CANDLE HOLDER

Ralph O. Johnson, Bristol, Conn., assignor to Associated Spring Corporation, Bristol, Conn., a corporation of Delaware

Application August 18, 1955, Serial No. 37,557

Term of patent 7 years

(Cl. D48—2)

Fig. 1 is a perspective view of a candle holder showing my new design;

Fig. 2 is a top plan view of the candle holder shown in Fig. 1, and

Fig. 3 is an end view of the candle holder shown in Fig. 1.

I claim:

The ornamental design for a candle holder, as shown.
